* cited by examiner

Primary Examiner — Susan Bennett Hattan*Assistant Examiner* — Brett Miller(74) *Attorney, Agent, or Firm* — Sughrue Mion, PLLC; Richard C. Turner(57) **CLAIM**

The ornamental design for a charger for electric vehicles, as shown and described.

DESCRIPTION

FIG. 1 is a front, top and right side perspective view of an embodiment of our new design;

FIG. 2 is a rear, top and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross-sectional view thereof; taken along line 9-9 of FIG. 7, with the internal system omitted.

The broken lines depict environmental subject matter that forms no part of the claim.
